EX

DESIGN FOR A RAILING.

UNITED STATES PATENT OFFICE.

WILLIAM C. HANNA, JR., OF NEW YORK, N. Y., ASSIGNOR TO J. W. FISKE,
OF SAME PLACE.

DESIGN FOR A RAILING.

SPECIFICATION forming part of Design No. 18,858, dated January 15, 1889.

Application filed September 21, 1888. Serial No. 286,048. Term of patent 7 years.

To all whom it may concern:

Be it known that I, WILLIAM C. HANNA, Jr., of New York, in the county of New York and State of New York, have invented a certain 5 new and original Design for a Railing, of which the following is a specification.

My invention consists of a new and original design for a railing for use on steps, porches, &c.

10 The accompanying photograph shows the railing in side elevation.

The design consists of three parallel bars, A, B, and C, connected by a series of upright bars or posts, D, which latter thus divide the 15 railing into a series of panels, as shown in the photograph. In each of these panels is an ornament consisting of two semicircular bars, a and b, with a series of rods, c, arranged radially, their outer ends projecting beyond the 20 outer semicircle, b, and being waved as shown. The central rod of the series is continued or projected upward beyond the rail B, and has its end curved or bent into the form of a scroll. That portion of this central rod which

is between the semicircle b and the rail B is 25 curved back and forth in a serpentine manner to form an ornament, d, in the center of the panel. The posts D are rectangular in cross-section and have a portion of their body twisted, as shown, to render them more 30 ornamental.

The various parts thus combined and arranged form a design for a railing that is highly ornamental and especially suitable for architectural purposes.

35 What I claim is—

The herein-described design for a railing, consisting of a panel formed by the posts D and rails A, B, and C, and the central ornament composed of the parts a, b, c, and d, substantially as shown.

In witness whereof I hereunto set my hand in the presence of two witnesses.

WM. C. HANNA, JR.
